(Cl. D81—10)

To all whom it may concern:

Be it known that we, Joseph Newman White and Jay Fred King, both citizens of the United States of America, residing respectively in Atlanta, in the county of Fulton and State of Georgia, and Marietta, in the county of Cobb and State of Georgia, have invented a new, original, and ornamental Design for a Gas Heater, of which the following is a specification, reference being had to the accompanying drawings, forming a part thereof.

In the drawings.

Figure 1 is a perspective view of a gas heater, embodying our new design, as viewed from the front of the heater,

Figure 2 is a top plan view,

Figure 3 is a perspective view looking from the rear of the heater,

Figure 4 is a side elevational view.

We claim:

The ornamental design for a gas heater, as shown.

JOSEPH NEWMAN WHITE.
JAY FRED KING.
